I. E. QUIST

CABLE GUARD

Filed Oct. 6, 1926

UNITED STATES PATENT OFFICE.

IRVING E. QUIST, OF WARREN, MINNESOTA.

CABLE GUARD.

Application filed October 6, 1926. Serial No. 139,944.

This invention relates to an improvement in cable guards of the type forming the subject-matter of my copending application filed March 29, 1926, Serial No. 98,284.

5 The object of the invention is to provide an improved cable guard of this character which has all of the advantages of the cable guard forming the subject-matter of the application referred to and which has additional advantages in that it is adapted to be manufactured at a comparatively slight expense from materials and by means of facilities ordinarily available.

10 A further object is to provide a cable guard having these advantages and capacities and wherein the brackets used to support the cable in spaced relation to the posts are so constructed and designed as to be adapted to about the posts over a relatively wide area and to be secured to the post by the same means that is employed to fasten the cable to the brackets.

15 A further object is to provide a cable guard wherein the brackets are so constructed that they may be applied to the posts without changing the posts in any way or even marring the band thereof. The brackets and fastening means associated therewith have the further advantage of being adjustable to properly tension the cable and of providing a stiff, strong and rigid guard assembly which will hold the automobiles on the road while inflicting a minimum of injury thereto.

20 35 Other objects and advantages reside in certain novel features of the construction, arrangement and combination of parts which will be hereinafter more fully described and particularly pointed out in the appended claims, reference being had to the accompanying drawings forming a part of this specification, and in which:—

Figure 1 is a perspective view showing one embodiment of the invention,

25 Figure 2 is a view in central horizontal section, and

Figure 3 is a detail plan view showing a blank from which the bracket is constructed.

Referring to the drawings it will be seen that the cable guard embodying the present invention is of the type including a number of posts 1 on which a heavy wire guard cable 2 is supported. Each post car-

ries a bracket 3 and each bracket 3 comprises a curved body plate 4 shaped to snugly fit against its post 1. The plate 4 engages the post 1 over a relatively large area. All of the elements of the bracket may be and preferably are constructed from a single piece of metal, a blank from which a bracket is constructed being shown in Fig. 3. As shown in the drawings converging side plates 5 are integrally formed at the side edges of the plate 4 of each bracket and these converging side plates 5 taper toward their outer ends. At their outer ends the side plates 5 are notched, as at 6, to provide a cable seat. The upper and lower edges of the side plates 5 are formed with connecting wings 7 which overlap in the assembly and are riveted together, as at 8.

A single means is provided for securing the cable 2 of each bracket 3 and for securing each bracket 3 to its post 1. This means preferably comprises an elongated bolt 10 the shank of which extends through an opening 11 in the post 1. The rearward end of the shank is externally threaded, as at 12, and co-acts with a nut 13. Between the nut 13 and the rear portion of the post 10 a washer 14 is interposed. The outer end of the shank of the bolt 10 is formed with a hook 16 which embraces the cable and holds the same on the seat constituted by the notches 6. The portion of the hook 16 which lies on the outside of the cable 2 may be flattened so that this hook presents a minimum obstruction on the cable. The major portion of each hook is housed and protected within its bracket 5. When the nut 13 is tightened up the bracket is drawn snugly against the post and the cable is drawn snugly against the bracket. In this way the cable is tensioned and is firmly and rigidly held on the post but is spaced inwardly 95 therefrom so that an automobile striking the guard cable will be deflected along the same so as to be held on the road and yet the automobile cannot collide with the posts and be thereby damaged. It is to be understood that any suitable number of posts are provided and that there is a bracket on each post. The ends of the cable are suitably anchored.

I claim:—

1. A bracket for use in supporting a guard

- 5 cable on a post comprising a body plate designed to snugly fit the post, converging side plates carried by said body and having a cable seat at their outer ends, and means for connecting said side plates.
- 10 2. A bracket for use in supporting a guard cable on a post comprising a body plate to snugly fit the post, converging side plates carried by said body and having wings 20 formed on their upper and lower edges, the wings of the opposed side plates overlapping and secured together, and the outer ends of 25 said plate being formed with a cable seat.
- 15 3. A bracket for use in supporting a guard cable on a post comprising a curved body plate designed to snugly fit the post, converging side plates integral with the body 30
- plate and tapering toward their outer ends, the outer ends of the side plates being formed with a cable seat, and means for connecting the side plates.
4. A bracket for use in supporting a guard cable on a post comprising a curved body plate designed to snugly fit the post, converging side plates integral with the body 25 plate and tapering toward their outer ends, the outer ends of the side plates being formed with a cable seat, and integral wings 30 formed on the upper and lower edges of the side plates, the wings of the opposed side plates overlapping and being secured together.

IRVING E. QUIST.
